(57) **CLAIM**

We claim the ornamental design for a hydration reservoir with a handle, as shown and described.

DESCRIPTION

FIG. 1 is an isometric view of a hydration reservoir with a hydration reservoir handle;

FIG. 2 is a front elevation view of the hydration reservoir of FIG. 1;

FIG. 3 is a rear elevation view of the hydration reservoir of FIG. 1;

FIG. 4 is a right side elevation view of the hydration reservoir of FIG. 1;

FIG. 5 is a left side elevation view of the hydration reservoir of FIG. 1;

FIG. 6 is a top plan view of the hydration reservoir of FIG. 1; and,

FIG. 7 is a bottom plan view of the hydration reservoir of FIG. 1.

The broken lines depict portions of the article that form no part of the claimed design.
